LOCK TUMBLER

Phillip W. Olson, Grand Rapids, Mich., assignor
to Automatic Instrument Company, Grand
Rapids, Mich., a corporation of Michigan

Application February 20, 1934, Serial No. 712,240

4 Claims. (Cl. 70—358)

This invention relates to improvements in locks, and more particularly to improvements in the construction and arrangement of the lock tumblers.

- 5 Objects of the invention are to increase the safety of the lock and to make it more difficult to "pick" the lock or to operate it in any manner without the use of the proper key; to provide a lock in which the significant surfaces of the key 10 are more difficult to ascertain for the purpose of duplication; and to provide a lock in which it is practically impossible to position the tumblers so that an impression can be taken for making a key all so that the plug may be turned.
- 15 Other objects are to provide a construction by which a greater number of tumbler combinations may be provided in the same length of plug, and to provide two available movements for each tumbler element so as to greatly multiply the 20 possible combinations for a given number of standardized tumbler patterns.

Further objects are to simplify the plug construction and reduce the number of operations necessary for fabricating or forming the parts; 25 and to simplify and facilitate the assembling operations.

Heretofore it has been necessary to provide in the plugs, in addition to the tumbler slots, pins or other abutment surfaces for the tumbler 30 springs, while in this invention the tumblers are self contained, being divided into parts with the springs contained within the parts for separating them to press the tumblers outwardly the amount permitted by the spring. Accordingly the slots 35 may be perfectly straight, and the springs may be mounted in the tumblers, and each of the tumblers assembled as an individual unit in its slot.

Shoulders for abutting against the top and 40 bottom of the key are provided on the tumbler elements for limiting their outward movement. This facilitates the assembling of the plug into the lock barrel, and prevents wear and battering of the ends of the tumbler plates against the 45 bottom of the locking grooves in the barrel which might tend to decrease the accuracy necessary in positioning the tumblers for unlocking or otherwise interfere with the operation of the lock.

50 The invention is embodied in the lock shown in the accompanying drawing, in which:

Fig. 1 is a transverse section through the lock taken on the line 1—1 of Fig. 3.

Fig. 2 is an end view of the plug cylinder.

55 Fig. 3 is a plan view of the plug, with an end

portion broken away to show a portion of the interior and parts contained therein.

Fig. 4 is a longitudinal section of the plug, taken on the line 4—4 of Fig. 2.

Fig. 5 is a perspective view of one of the composite tumblers.

Fig. 6 is a view taken the same as Fig. 4, showing the tumblers retracted into the plug by the insertion of the key.

Fig. 7 is a view of the key turned over to show 10 the groove for operating the tumblers, as shown in Fig. 6, in full lines, it being understood that the key is provided with a deviating groove in each side which is formed suitably for operating the lateral set of tumblers related therewith. 15

The barrel or casing 6, which is to be fixedly mounted in a lock housing structure, is of a hollow cylindrical formation, and has pairs of oppositely disposed longitudinal locking grooves 9 in the bore 10 thereof, for accommodating two oppositely disposed sets of tumblers 11, in the particular type of lock shown.

As will become obvious, the features of invention may be used as well in other types of construction, which may have only one row of tumblers, different arrangements of the rows and so on, or the barrel possibly may have a groove only in one side so that the tumblers project from the plug in only one direction.

In the construction shown, the key plug 8 is 30 made of two complementary halves 12 and 13, which are secured together by end rings 14. The faces of the halves are milled longitudinally to provide, when assembled, a longitudinal keyway 35 of rectangular cross section 15 extending therethrough, and the halves are milled transversely to provide tumbler slots 16, at each side of the keyway, and interlocking fingers 17 which form the inner sides of the slots and insure proper alignment between the halves. Aside from the 40 plain keyway and tumbler slots, there are no special provisions necessary in the construction of the plug cylinder. The plug is rotatably mounted in the barrel, and may be restrained from longitudinal movement in the barrel in any 45 suitable manner, and may have any suitable means for making an operative connection to the bolt of the lock, not shown.

The tumbler elements 11 comprise two plates 50 18 and 19 which conform in length to the slots 50 so that the plates may be positioned for unlocking with both ends thereof flush with the surface of the plug; and the slightest movement in either direction will cause either one end or the other to project and engage the side of a groove 9 of 55

the casing 8. The plates each have a longitudinal recess or central aperture 20 which register laterally to form a pocket for receiving a coiled wire tumbler spring 21. Thus the spring is compressed longitudinally between the ends of the apertures, and serves to press the plates outwardly from the plug in opposite directions for locking engagement in the grooves 9 to prevent the rotation of the plug. The separation of the plates is stopped when the apertures are in registration and the two plates become a tumbler which is longer than the diameter of the plug.

10 The outward movement of the plates may be limited in the plug by a shoulder 22, which is formed on the inner edges of the plates and abuts against the top or bottom of the keyway, according to the direction of movement of the particular plate; and each plate is provided with a key engagement lug 23 which projects 20 into the keyway.

15 The tumblers are retracted and drawn in flush with the surface of the plug by the insertion of a key 24. The key is notched at the end for engaging the pairs of lugs 23 and drawing the parts of the tumblers together; and is provided, in each side, with an irregular groove 25 which is formed to provide surfaces in the sides thereof for accurately positioning the tumblers for 25 unlocking when the key is fully inserted. The 30 sides of the groove have no relation with each other because the lugs of the plates which are drawn upwardly bear against the lower side of the groove, and the lugs which are drawn downwardly bear against the upper side, the grooves being wider than the length of the lugs.

35 The depth of the insertion of the key is determined by shoulders 26, provided on the shank of the key, which abut against the face of the plug so that the tumbler positioning surfaces in the sides of the grooves are placed in registration with the corresponding lugs.

40 For obtaining different combinations, the lugs are located at different places along the edges of the plates. Thus one plate pattern may 45 have the lug in the middle so that the lug must be positioned along the axis of the keyway; another pattern may have the lug offset toward one end of the plate a short distance; and a third pattern may have lugs offset a greater 50 distance.

55 Thus each pair of plates may be varied by using different combinations, reversals, and relative transpositions of the three plate patterns, as well as different consecutive arrangements of patterns in the slots for making up the combinations.

By using double tumblers, the number of double tumbler elements are doubled in the same

size of plug. Each double tumbler with its spring is a self contained unit, and may be easily assembled by placing the two plates together, inserting the springs, and then laying the tumbler in its slot, the springs being then held from jumping out while the halves of the tumbler are being assembled.

5 Thus the two tumbler halves become the holder for the spring in placing the spring into the plug. Since the springs are quite minute in 10 size, considerable difficulty is often met in having the springs jump out of position, or become disarranged during the assembling of the other parts of the plug. The installing of the springs and tumblers is greatly simplified, and considerable time is saved thereby, which reduces the 15 cost of the locks in quantity production.

Having thus described my invention, I claim:

1. A lock comprising a pair of tumblers, a cylindrical plug having a longitudinal key-way 20 with a transverse tumbler slot, a pair of tumblers arranged side by side and movable in opposite directions in the same slot, the tumblers having median apertures, and a spring compressed between the apertures of the tumblers 25 and retained therein by the sides of the slot and tending to press the tumblers outwardly from the opposite sides of the plug.

2. A lock comprising a cylindrical plug consisting of a pair of semi-cylindrical members together providing a longitudinal key-way having transverse tumbler slots in each member intersecting the key-way, tumblers comprising two centrally apertured plates slidably fitting in each tumbler slot, and a spring compressed within 35 the apertures of each pair of tumblers and confined therein by the sides of the tumbler slot and tending to press the tumblers outwardly from opposite sides of the plug.

3. A lock comprising a cylindrical plug having 40 a longitudinal key-way with transverse tumbler slots intersecting the key-way at opposite sides, a plurality of pairs of tumblers, each pair fitting slidably in a tumbler slot and having double tumbler ends, each pair of tumblers having 45 median apertures and an extended coil spring compressible within the joint apertures of each pair of tumblers and tending to press the tumblers in opposite directions, and each tumbler having a lateral projection at its edge extending 50 into the key-way for engagement with a key for drawing the tumblers into the plug for unlocking.

4. A structure in accordance with claim 3 in which the edges of the tumblers have shoulders 55 for engagement with the top and bottom of the key-way for limiting their outward movement.

PHILLIP W. OLSON.
